US0D1031680S

(12) **United States Design Patent** (10) Patent No.: **US D1,031,680 S**
(45) Date of Patent: ** Jun. 18, 2024

(54) **TELEVISION**

(71) Applicant: **BELJING XIAOMI MOBILE SOFTWARE CO., LTD.**, Beijing (CN)
(72) Inventor: **Yunlong Zhang**, Beijing (CN)
(73) Assignee: **BELJING XIAOMI MOBILE SOFTWARE CO., LTD.**, Beijing (CN)

(**) Term: **15 Years**

(21) Appl. No.: **35/513,652**

(22) Filed: **Oct. 13, 2021**

(80) **Hague Agreement Data**

Int. Filing Date: **Oct. 13, 2021**

Int. Reg. No.: **DM/218808**

Int. Reg. Date: **Oct. 13, 2021**

Int. Reg. Pub. Date: **Feb. 18, 2022**

(30) **Foreign Application Priority Data**

(57) **CLAIM**

The ornamental design for a television, as shown and described.

DESCRIPTION

1.1 is a front view showing a television of our new design;
1.2 is a back view thereof;
1.3 is a left view thereof;
1.4 is a right view thereof;
1.5. is a top view thereof;
1.6 is a bottom view thereof; and
1.7 is a perspective view thereof.
